SHEET CLAMPING ARRANGEMENT FOR
FACSIMILE APPARATUS

Russell G. Thompson, Rochester, N. Y., assignor
to Eastman Kodak Company, Rochester, N. Y.,
a corporation of New Jersey

Application November 15, 1950, Serial No. 195,726

5 Claims. (Cl. 346—138)

1

This invention relates to a sheet clamping arrangement for facsimile apparatus and more particularly to a sheet clamping arrangement for securing sheets of variable width and/or length to the scanning drum of such apparatus.

In facsimile systems, the picture or information to be transmitted is generally wrapped around the surface of a drum which is rotated past a scanning beam of light. Since the drum is of a fixed size, the sheet to be wrapped around said drum is usually of such size that the leading and trailing edges are secured adjacent each other by the same or similar clamping means. In the event that the sheet is not sufficiently long or wide so that both edges can be clamped, elastic rings are sometimes utilized for holding the sheet in contact with the drum. The prior devices further require that the operator smooth the sheet as it is wrapped around the drum and secured thereto and do not provide a satisfactory arrangement for efficiently handling sheets of variable width and/or length.

The present invention contemplates a rotatable drum provided with sheet holding means adapted to accommodate sheets differing, within limits, in width and/or length. With the present invention, the operator is required to merely insert one edge of the sheet beneath the clamping bar and manually rotate the drum. As the drum is rotated, the leading edge of the sheet is immediately clamped in position on the drum, and the sheet is smoothed and wrapped around the drum by a plurality of spaced rollers. The drum is rotated until the rollers are positioned adjacent the trailing edge of the sheet, and upon release of a clutch member, the rollers are rotatable with the drum during the scanning operation. The rollers, therefore, smooth the sheet as it is wrapped on the drum, are positioned peripherally of the drum in accordance with the location of the trailing edge of the sheet, and maintain the sheet in contact with the drum as it is being scanned.

The primary object of the invention is to provide a sheet clamping device for facsimile apparatus which will accommodate sheets differing, within limits, in width and/or length.

Another object of the invention is to provide a holding means for the trailing edge of the sheet which is movable peripherally of the drum to a position in accordance with the location of the trailing edge of the sheet on the drum and which is rotatable with the drum.

And another object of the invention is to provide means whereby the holding means is held

2

against rotation with the drum so that the drum may be rotated relative thereto in a direction opposite to its predetermined direction of rotation for actuating the clamping bar to a released position and may be rotated relative thereto in its predetermined direction to permit the clamping bar to return to its normal or clamping position and to smooth the sheet onto said drum as the holding means is positioned adjacent the trailing edge of the sheet.

Other objects and advantages will be apparent to those skilled in the art by the description which follows.

Since the present invention accommodates sheets differing in width, the underlap period during which the recorder should print "white," i. e., not reproduce the separation between the leading and trailing edges of the sheet, is also variable. Accordingly, the provision of a means adjustable with the manipulation of the sheet holding means for transmitting "white" during the underlap period, as determined by the width of the sheet secured to the drum, is disclosed in my copending application, Serial No. 169,992, filed June 23, 1950.

The term "leading edge," as used in the following description of the invention and in the appended claims, is that edge of the sheet at which the scanning begins, and the term "trailing edge" is that edge of the sheet at which the scanning ends. In the present invention the leading edge of the sheet is secured to the drum by the clamping bar and the sheet is maintained in contact with the drum by the plurality of rollers engaging the trailing edge.

Reference is now made to the accompanying drawings wherein like reference numerals designate like parts and wherein:

Fig. 1 is a partial view in perspective of a facsimile apparatus embodying the preferred form of the invention;

Fig. 2 is a plan view of the clutch actuating and drive mechanism adjacent one end of the rotatable drum;

Fig. 3 is an end view of the drum and showing the mounting arrangement for the sheet or paper bail;

Fig. 4 is a partial plan view of a portion of the drum and showing the clamping bar;

Fig. 5 is a partial vertical section through the drum and clamping bar;

Figs. 6, 7 and 8 are sectional views of details of the clamping bar shown in Figs. 4 and 5;

Fig. 9 is an end view of the drum and showing the position of the actuating means with re-

spect to the actuating pin just prior to raising of the clamping bar to its releasing position and with the paper bail latched against rotation; and

Fig. 10 is an end view of the drum and showing one of the positions of the actuating means for the clamping bar with respect to the actuating pin on the paper bail in its latched position.

The facsimile apparatus, as shown in Fig. 1, discloses only the drum portion of the apparatus, since the apparatus is of the well-known type in which the transmitting drum and recording drum have a common shaft. The recording drum forms no part of the present invention and has, therefore, been omitted. A scanning unit 10 is of any well-known structure for projecting a beam of light onto the sheet 11 and for deriving electric signals corresponding to the light-reflecting properties of successive elemental areas of the picture or information on sheet 11. The drum 12 is rotated at a constant rate while the scanning unit moves along the drum parallel to its axis in a well-known manner. The drum 12 is mounted on shaft 13 which is adapted to be driven in a direction indicated by the arrow in Fig. 1. The drive means for drum 12 comprises a suitable motor 14, a worm 15, a worm gear 16 and two clutch members 17 and 18. The clutch member 17 is carried by worm gear 16 and contains a clutch socket while clutch member 18, which has a clutch cone, is keyed to but free to move longitudinally of shaft 13. Clutch member 17 and worm gear 16 are freely rotatable on shaft 13 but are restrained from longitudinal movement by any suitable means such as a collar 19 secured to shaft 13.

As shown in Figs. 1 and 4-8, a clamping bar 21 extends longitudinally of drum 12 for securing the leading edge of sheet 11 thereto. Clamping bar 21 is biased to a clamping position against plate 22 by means of springs 23 which are under compression between the under surface of plate 22 and the heads of the guide members or studs 24 extending radially through plate 22 and secured to and spaced along clamping bar 21, as shown in Figs. 1 and 5.

The clamping bar 21 is moved radially to a position for releasing the edge of the sheet secured thereunder by an actuating means comprising a cam shaft 26 common to all studs 24 and crank members 27 which are operated in a manner to be described hereinafter. Cam shaft 26 extends through the ends of drum 12, is rotatable with drum 12, and has cam surfaces 28 formed by grinding flats in said shaft. These cam surfaces are ground to a depth sufficient to clear the heads of studs 24 at their lowest limit of travel, as shown in Fig. 6, and permits a limited rotation of shaft 26 without moving bar 21. Referring now to Figs. 5 and 8, it will be noted that shaft 26 has an additional flat 29 at each end thereof against which a floating follower 30 is pressed by spring 31 under compression between plate 22 and follower 30. This cam flat 29 is milled to a depth which is less than the radius of shaft 26 so that said shaft is stabilized in the position shown in Fig. 8, i. e., shaft 26 is unstable in any other angular position in which the face of follower 30 is not tangent to the circular portion of shaft 26. This stabilized position of shaft 26 is such that the bifurcated crank members 27 secured to the ends of shaft 26 are maintained in the position shown in Figs. 9 and 10. The clearance provided between flats 28 and studs 24 allows cranks 27 to be rotated through a small angle in a clockwise direction without affecting

clamping bar 21 for reasons to be described hereinafter.

The means for holding the trailing edge of sheet 11 in contact with drum 12 is best shown in Figs. 2 and 3 and comprises support or bail plates 35, a shaft 36 extending therebetween and parallel to drum 12, and a plurality of spaced rollers 37 spaced along shaft 36, as shown in Fig. 1 to form a paper bail 38. The bail plates 35 are provided with slotted apertures 39 through which shaft 13 extends, the aperture bearing against shaft 13 in one dimension but being larger than shaft 13 in the other dimension to permit sheets of differing thickness to pass between rollers 37 and drum 12. A spring 43 under tension between a formed-out ear 41 on plate 35 and the formed-out end of an arm 42 having its other end pivotally secured at 43 to plate 35 performs the dual functions of biasing the paper bail 38 against the surface of drum 12 and of pressing a roller 44 carried by arm 42 into engagement with a detent wheel or drive member 45 secured to drum 12. By reason of spring pressed roller 44 engaging detent wheel 45, bail plates 35 can easily be rotated with respect to drum 12 but will, in the absence of an outside force, rotate with drum 12. A counterweight 46 is attached to plates 35 for balancing purposes. An actuating member or pin 47 extends from plates 35 toward drum 12 and a latching member or pin 48 extends outwardly for purposes described hereinafter.

The means for releasing the clutch members 17 and 18 to disconnect the drive means from drum 12 and for moving the latching means 49 into an engaging position comprises a linkage 50 which is manually operable upon completion of the scanning operation to release sheet 11 from drum 12 or to clamp the leading edge of a sheet to said drum. The release means is best disclosed in Figs. 1 and 2 in which a clutch lever 51 is pivoted at 52 to frame 53 of the apparatus and has an ear 54 provided with a pin 55 extending into a circumferential groove in clutch member 18. A compression spring 56 between clutch member 18 and collar 57 which is secured to shaft 13 serves to bias clutch member 18 into engagement with clutch member 17. A cam 59, when rotated by handle 60 through 90 degrees and into the position shown in Fig. 1 moves clutch lever 51 to the right and thereby disengages clutch members 17 and 18 to stop rotation of shaft 13 while the worm gear 16 continues to be rotated by motor 14. Any other suitable clutch mechanism may, of course, be employed. With the clutch members disengaged, shaft 13 may be readily rotated by the hand wheel 61 secured thereto.

With handle 60 in the position shown in Fig. 1, clutch lever 51 is in the disengaging, or release, position and the riser on cam 59 abuts lever 51, and follower 62 carried on one end of lever 63, which is pivotally mounted at 63' on boss 64 provided on a portion of frame 53, is in engagement with the low portion of said cam. The other end of cam follower lever 63 is connected through a link 65 to a crank arm 66 to control the angular position of a rod 67 extending parallel to drum 12 and carrying the latching means or members 49. The follower 62 is urged against the cam by springs 68 secured to the ends of members 49. Thus, when handle 60 is rotated to the right to engage the clutch members 17 and 18, the riser 75 of cam 59 elevates the follower 62 and rotates

rod 67 to move latch members 49 out of the path of pins 48.

In order to insert one end of a sheet under the clamping bar 21, handle 60 is turned from its normal position to the position shown in Fig. 1. As handle 60 is moved to this position, the clutch members 17 and 18 are disengaged and latch members 49 are moved into the path of pins 48, see Figs. 9 and 10. The handwheel 61 is then rotated in the direction of the arrow, which is the direction of the scanning operation, until latch members 49 engage and latch pins 48 on bail plates 35. The handwheel 61 is now rotated in the opposite direction to rotate drum 12 relatively to the stationary bail 38 until the bifurcated ends of the cranks 27 receive pins 47 carried by bail plates 35, as shown in Fig. 9. Rotation of drum 12 is continued until crank members 27 have been rotated about 90 degrees and movement of the drum is arrested by lug 69 on crank 27 engaging the reduced end portion 70 of drum 12, as shown in Fig. 3. This rotation of crank members 27 turns cam shaft 26 to raise the clamping bar 21 to the position shown in Fig. 7 thereby permitting the edge of sheet 11 to be inserted thereunder.

The handwheel 61 is then rotated in the direction of scanning and releases pins 47 from crank members 27 to permit followers 30 to return shaft 26, crank members 27 and clamping bar 21 to the position shown in Fig. 6 and in which position the edge of sheet 11 is clamped to drum 12 between plate 22 and clamping bar 21. Continued turning of the handwheel 61 rotates drum 12 and sheet 11 relative to the paper bail 38, the sheet being moved under rollers 37 and wrapped smoothly on the drum. After the drum has been turned to a position in which rollers 37 are adjacent the trailing edge of sheet 11, as shown in Fig. 1, the handle 60 is returned to the clutch-engaging position which releases members 49 from pins 48 so that the entire assembly of drum, clamping bar, sheet and paper bail will be rotated as a unit for scanning operation.

At the end of scanning operation, the same steps are taken to release clamping bar 21 for removing sheet 11 from the drum 12. With the clamping bar 21 in its releasing position, another sheet can immediately be inserted thereunder to complete another scanning operation. Since the slot 71 in the latch member 49 engages pin 48 and prevents rotation in either direction, the paper bail 38 is always arrested in the same position with respect to the horizontal, as shown in Fig. 3. Consequently, the clamping bar 21 in its released position for having a sheet placed thereunder or withdrawn therefrom also assumes the same relative position with respect to the paper bail because of the relative location of pins 47 and 48 on bail plates 35.

While for the purpose of disclosing the invention, only a specific embodiment has been described in detail with respect to facsimile apparatus, it will be apparent to those skilled in the art that the invention may be applied to other apparatus and that many other embodiments may be devised without departing from the invention, the scope of which is pointed out in the appended claims.

What I claim as new and desire to secure by Letters Patent of the United States is:

1. A clamping device for securing a sheet of material to a rotatable drum comprising a clamping bar extending longitudinally of said drum for clamping the leading edge of said sheet to said

drum, a plurality of guide members secured to said clamping bar and spaced longitudinally of and extending radially of said drum, resilient means for biasing said guide members and maintaining said clamping bar in a clamping position, an actuating means operatively connected to said guide members and rotatable with said drum and adapted to move said guide members and clamping bar to a position for releasing said edge, a plurality of rollers spaced axially of said drum and in contact therewith for holding the trailing edge of said sheet in contact with said drum, a drive member at each end of said drum and operatively connected thereto for rotation therewith, and support members at each end of said drum and operatively connected to said drive members and for supporting said rollers therebetween, said support members and rollers being rotatable about the axis of rotation of said drum independently of said drive members for positioning said rollers peripherally of said drum in accordance with the location of the trailing edge of said sheet on said drum and adapted upon movement of said drum relative thereto to trip said actuating means.

2. A clamping device for securing a sheet of material to a rotatable drum comprising a clamping bar extending longitudinally of said drum for clamping the leading edge of said sheet to said drum and adapted to be moved radially of said drum to a position for releasing said edge, holding means rotatable with said drum for maintaining the trailing edge of said sheet in contact with said drum and adapted to be positioned peripherally of said drum in accordance with the location of the trailing edge of said sheet on said drum, a drive means for rotating said drum in a predetermined direction, means operatively connected to said drive means and movable to a position for disconnecting said drive means from said drum and for engaging said holding means to prevent rotation thereof upon rotation of said drum in said predetermined direction, and a second drive means operatively connected to said drum and manually operable upon disconnection of said drive means for rotating said drum in said predetermined direction and relative to said holding means to position said holding means adjacent the trailing edge of said sheet on said drum.

3. A clamping device for securing a sheet of material to a rotatable drum comprising a clamping bar extending longitudinally of said drum for clamping the leading edge of said sheet to said drum and adapted to be moved radially of said drum to a position for releasing said edge, an actuating means operatively connected to said clamping bar and rotatable with said drum and adapted to move said clamping bar to said releasing position, holding means rotatable with said drum for maintaining the trailing edge of said sheet in contact with said drum and adapted to be positioned peripherally of said drum in accordance with the location of the trailing edge of said sheet on said drum, a drive means for rotating said drum in a predetermined direction, means operatively connected to said drive means and movable to a position for disconnecting said drive means from said drum and for engaging said holding means to prevent rotation thereof upon rotation of said drum, and a second drive means operatively connected to said drum and manually operable upon disconnection of said drive means for rotating said drum in a direction opposite to said predetermined direction and relative to said holding means to a position in which said holding

means operates said actuating means and for rotating said drum in said predetermined direction and relative to said holding means to position said holding means adjacent the trailing edge of the sheet on said drum.

4. A clamping device for securing a sheet of material to a rotatable drum comprising a clamping bar extending longitudinally of said drum for clamping the leading edge of said sheet and adapted to be moved radially of said drum to a position for releasing said edge, an actuating means operatively connected to said clamping bar and rotatable with said drum and adapted to move said clamping bar to said releasing position, holding means movable with said drum for maintaining the trailing edge of said sheet in contact with said drum and adapted to be rotated independently of said drum to a position in accordance with the location of the trailing edge of said sheet on said drum, a drive means for rotating said drum in a predetermined direction, latching means adapted to be moved into a position for engaging said holding means for preventing rotation of said drum in said predetermined direction, release means operatively connected to said drive means and said latching means and movable to a position for disconnecting said drive means from said drum and moving said latching means into its engaging position, and a second drive means connected to said drum and manually operable upon movement of said release means to said position for rotating said drum in said predetermined direction until said latching means engages said holding means, for rotating said drum in a direction opposite to said predetermined direction and relative to said holding means to a position in which said holding means operates said actuating means, and for rotating said drum in said predetermined direction and relative to said holding means to release said actuating means and to position said holding means adjacent the trailing edge of the sheet on said drum.

5. A clamping device for securing a sheet of material to a rotatable drum comprising a clamping bar extending longitudinally of said drum for clamping the leading edge of said sheet to said drum, a plurality of guide members secured to said clamping bar and spaced longitudinally of and extending radially of said drum, resilient means for biasing said guide members and maintaining said clamping bar in a clamping position, an actuating means operatively connected to said

guide members and rotatable with said drum and adapted to move said guide members radially to position said clamping bar in a position for releasing said edge, a plurality of rollers spaced axially of said drum and in contact therewith for holding the trailing edge of said sheet in contact with said drum, a drive member at each end of said drum and operatively connected thereto for rotation therewith, a support member at each end of said drum having a latch member and a part adapted to engage said actuating means and operatively connected to said drive members and for supporting said rollers therebetween, said support members and rollers being rotatable about the axis of said drum and adapted to be positioned peripherally of said independently driven members, in accordance with the location of the trailing edge of said sheet on said drum, a drive means for rotating said drum in a predetermined direction, latching means adapted to be moved into a position for engaging said latch members to prevent rotation of said support members, release means operatively connected to said drive means and said latching means and movable to a position for disconnecting said drive means from said drum and moving said latching means into said engaging position, and a second drive means operatively connected to said drum and manually operable upon movement of said release means to said position for rotating said drum in its predetermined direction until said latching means engages said latch member, for rotating said drum in the opposite direction and relative to said support members to a position in which said actuating member operates said actuating means, and for rotating said drum in said predetermined direction relative to said support member to release said actuating means and to position said rollers adjacent the trailing edge of the sheet on said drum.
